(57) CLAIM

The ornamental design for a fender mirror, as shown and described.

DESCRIPTION

FIG. 1 is a perspective view of a first embodiment of this

invention with a mounting post and adjacent screws shown in broken lines, with features shown in broken lines not forming part of the claimed invention;

FIG. 2 is a front elevation view of a first embodiment of this invention;

FIG. 3 is a left side view of a first embodiment of this invention, the right side view being a mirror image;

FIG. 4 is a top plan view of a first embodiment of this invention;

FIG. 5 is a rear elevation view of a first embodiment of this invention;

FIG. 6 is a bottom plan view of a first embodiment of this invention;

FIG. 7 is a perspective view of a second embodiment of this invention with a mounting post and adjacent screws shown in broken lines, with features shown in broken lines not forming part of the claimed invention;

FIG. 8 is a front elevation view of a second embodiment of this invention;

FIG. 9 is a left side view of a second embodiment of this invention, the right side view being a mirror image;

FIG. 10 is a top plan view of a second embodiment of this invention;

FIG. 11 is a rear elevation view of a second embodiment of this invention; and,

FIG. 12 is a bottom plan view of a second embodiment of this invention.
